IRONING PRESS

George W. Wardwell, Jr., Nichols, Conn., assignor to General Electric Company, a corporation of New York

Application October 30, 1934, Serial No. 750,620
Renewed June 1, 1938

37 Claims. (Cl. 38—25)

My invention relates to ironing presses of the type in which ironing is effected by the pressure between a buck and a heated shoe.

The object of my invention is to provide an improved arrangement and control in an ironing press of this type, and for a consideration of what I believe to be novel and my invention, attention is directed to the accompanying description and the claims appended thereto.

- 10 In the accompanying drawings, Fig. 1 is an end elevation partly in section of an ironing press embodying my invention; Fig. 2 is a plan view of the shoe and carriage; Fig. 3 is a fragmentary plan view partly broken away of the buck; Fig. 4 is a sectional view taken on line 4—4 of Fig. 3; Fig. 5 is a sectional view taken on line 5—5 of Fig. 2; Fig. 5a is an enlarged portion of Fig. 5; Fig. 6 is a sectional view taken on line 6—6 of Fig. 1; Fig. 7 is a sectional view taken on line 7—7 of Fig. 1; Fig. 8 is a plan view of the bearing housing at the upper end of the piston which moves the buck into pressing engagement with the shoe; Fig. 9 is a perspective view of the spacer which prevents rearward tilting of the buck during pressing; Fig. 10 is a sectional view partly broken away taken on line 10—10 of Fig. 6; Fig. 11 is a diagrammatic view of the control for the ironing press; and Fig. 12 is a bottom plan view of the center of the back casting.
- 30 Referring to the drawings, the ironing machine is shown carried on a table having a table top 1 and supporting legs 2. The table top is reinforced by a channel 3 secured to the under side. An apron 4, secured to the rear edge of the table top, prevents the surplus of the material being ironed from falling over the rear edge of the table. At the front edge of the table top is a leaf 5 which is rotatably carried on the front edge of the table top by a pin 6. A brace 7 supports the leaf in the position shown in Fig. 1. The brace projects through a slot in the front edge of the table top and is provided with a notch 8 which engages the lower side of the slot. When the ironing machine is not in use, the free end 45 of the brace 7 is lifted so that it can slide through the slot in the table top, and the leaf is swung downwardly about the pin 6. Similar leaves may be provided at either end of the table.
- 50 The table top is provided with a central opening through which the lower end of a cylinder 9 projects. The cylinder is supported on the table top by a flange 10 integral with the cylinder and suitably secured to the table top. The axis of the cylinder is inclined downward and rearward from the vertical. The cylinder 9 forms the outer casing and stationary member of a power-operated device for moving the buck and shoe into pressing engagement. A piston 11 which forms the movable member of the power-operated device is slidably carried within the cylinder 9, as shown in Fig. 6. On the upper side of the piston is a motor casing 12, and on the upper end of the motor casing is a bearing housing 13. The piston, motor casing, and bearing housing are secured together by through bolts 14 so that all three move as a unit. A guiding flange 15 on the upper end of the motor casing assists in guiding the movement of the piston in the cylinder.
- 55 The cylinder is filled with a suitable fluid, such as oil, and the piston is moved upward in the cylinder by pressure between the lower end of the cylinder and the piston. This pressure is created by an impeller 22 driven by an electric motor carried in the upper end of the motor casing 12. The stationary member 16 of the electric motor is pressed into the upper end of the motor casing. The rotating member 17 of the electric motor is provided with a shaft 18 which is rotatably carried in a bearing 19 in the bearing housing 13 and in a bearing 20 in a bearing housing 21. The bearing housing 21 is integral with the motor casing and provides a partition which prevents the leakage of oil from the cylinder into the space around the motor. At the lower end of the motor shaft is secured the impeller 22. The impeller and the rotating member of the motor are supported by a spring-pressed ball 23 arranged in a recess 24 in a piston head 25. The piston head is secured to the lower end of the piston 11 by 35 studs 26. The piston head is spaced from the lower end of the piston and provides a chamber in which the impeller 22 rotates. A piston ring 25a lies in a groove between piston head 25 and piston 11. Rotation of the impeller by the motor causes oil to be drawn from the upper side of piston 11 through inlet opening 27 in the piston and to be forced outward through the space between the piston head 25 and the lower side of the piston. From here the oil flows through 45 openings 28 in the piston head and creates a pressure between the cylinder and the lower side of the piston head which moves the piston upward in the cylinder. The oil which flows through the inlet opening 27 enters from the 50 cylinder through openings 29 in the lower end of the motor casing and flows between a baffle plate 30 and the upper side of the piston 11 to the inlet opening. Vanes 31 are provided on the upper side of the piston which guide the oil to the 55

inlet opening 27 and prevent swirling of the oil at the inlet opening. The baffle plate 30 rests on the upper side of the vanes 31 and is held in place by peaning projections 32 on the upper side 5 of the piston over the edge of the baffle plate. The rotation of the impeller tends to create a pressure between the under side of the impeller and the upper side of the piston head which tends to lift the impeller away from the upper 10 side of the piston head. This thrust is resisted by a thrust pin 33 which is adjustably threaded into the upper end of the bearing housing 13 and which bears a disc 33^a of bearing material on the upper end of the shaft 18 of the electric motor. The disc 33^a provides a surface which will not wear sufficiently during the normal life of the ironer to destroy the end thrust adjustment. Holes 34 are provided in the impeller which tend to relieve the pressure on the under side of the impeller.

In the operation of the power-operated device, supplying current to the electric motor starts the rotation of the impeller, thereby causing oil to be pumped from the upper to the lower side 25 of the piston and building up a pressure between the cylinder and the lower side of the piston which causes the piston to be raised in the cylinder. Due to the time necessary for accelerating the electric motor, there is some time lag in 30 the building up of pressure by the impeller. This time lag causes the movement of the piston in the cylinder to be started smoothly. The upward movement of the piston continues until the resistance offered to the upward movement 35 of the piston balances the pressure created by the impeller between the cylinder and piston. When this condition is reached, there is no further upward travel of the piston, and the piston remains in this position as long as the 40 electric motor is energized. When the motor is deenergized, the impeller stops rotating and oil flows from the space between the lower end of the piston and the cylinder through openings 28 and inlet opening 27 to the upper side of 45 the piston, and the piston returns to the position illustrated in Fig. 6 under the action of gravity. The piston and cylinder cooperate to cushion the return movement. An opening 35 is provided in the flange 15 on the motor casing through which air may flow to the upper surface of the oil in the cylinder. This prevents the 50 creation of a suction by the reciprocating movement of the piston in the cylinder.

The buck is mounted on the upper side of 55 the bearing housing 13 and is reciprocated by the piston. The buck comprises a hollow casting 36 which is provided with a circular depending flange 37 which fits over the upper end of the cylinder 9. The buck casting is also provided with a pair of depending longitudinal ribs 38 which rest on shoulders 39 on the upper side of the bearing housing 13. These ribs and shoulders provide a tiltable support for the buck. The ribs 38 support the buck so that the upper surface of the buck is inclined upwardly from the front and so that the axis of the cylinder 9 inclines downwardly and rearwardly from the center line of the buck. It is easier for the operator to arrange clothes on the inclined surface of the buck. The buck is held in place on 60 the upper side of the bearing housing by studs 41 which pass through openings 42 in the bearing housing and are threaded into the lower side of the buck casting 36. Coil springs 40 arranged between the heads of studs 41 and the lower side

of the bearing housing bias the buck casting downward toward the bearing housing 13 so that the ribs 38 on the buck casting are resiliently held in engagement with the shoulders 39 on the bearing housing. The studs 41 are arranged on the longitudinal axis of the buck on either side of the center so that the buck is free to tilt in all directions in order to maintain an even pressure over the surface of the buck during pressing. In order to restrain rearward 10 tilting of the buck, for reasons which will appear hereinafter, a spacer 43 is placed across ribs 44 on the rear upper side of the bearing housing 13. The spacer is held in place by projections 45 which engage notches 46 in the bearing 15 housing. The spacer engages a pair of transverse ribs 46^a, which extend downwardly from the buck casting and thereby restrains rearward tilting of the buck. The spacer 43 does not restrain rearward tilting of the buck sufficiently 20 to destroy the flexibility of the buck mounting. The forward tilting of the buck is limited by the engagement of the front end of the ribs 46^a with the upper edge of the bearing housing 13. The buck mounting is such that there is less resistance to forward than to rearward tilting of 25 the buck. The buck casting 36 is hollow and is provided with spaced ribs 47 (Fig. 3) which extend upwardly from the upper surface of the casing and have their upper edges in line with 30 a shoulder 48 provided along the inner edge of the casting. Across the ribs 47 and the shoulder 48 is placed a wire mesh screen 49. The wire mesh screen supports pads 50 of textile material which are held in place on the screen 35 by a pad cover 51. The pad cover 51 is held in place by cords 52 which are laced across the under surface of the buck casting.

During ironing, the moisture in the clothing is transformed into steam which passes through 40 the pads 50 and the wire mesh screen 49 into the interior of the buck casting. When first starting to iron, the bottom walls of the buck casting are cold and the steam which passes through the padding is immediately condensed 45 on these walls. The condensed steam is led from the buck through an opening 53 in the lower wall of the buck casting and through a drain tube 54 secured in place in this opening. From the drain tube 54 the condensed moisture flows through an opening 55 in a bracket 56 secured to the side of the cylinder 9 and through a drain tube 57 secured in opening 55 to a drain trap 58. The drain trap 58 is preferably a glass 50 jar so that the amount of moisture contained therein will be visible from the outside. The drain trap is removably held in place on the bracket 56 by a clip 59. A vent 60 is provided in the bracket above the drain trap. The lower end of drain tube 57 extends near the bottom of the drain trap 58 so that by the time the bottom walls of the buck casting have become heated by the steam so that all the steam is not condensed therein, the lower end of the drain tube 57 is submerged. Since steam from the buck 65 must now pass through the relatively low temperature condensate in the drain trap, escape of steam from the buck is prevented. The space between the drain tube 54 and the bracket 56 is sealed by a resilient washer 61 held in 70 place in the upper end of the bracket by a retaining washer 62. The washer 61 permits tilting movement of the buck and also permits sliding movement of the buck relative to the cylinder without destroying the seal.

5 A U-shaped carriage 63 for supporting the shoe is pivotally carried at the lower end of the cylinder in ears 64 which depend from the cylinder. The carriage is keyed to a pin 65 which is rotatably mounted in the ears 64. The pin 65 is centered on the axis of the cylinder. With this arrangement, the thrust on the carriage during the ironing is not transferred to the table top. Also, since the pin 65 is located on the axis of the 10 cylinder, there is no tendency for the cylinder to tilt on the table top during pressing. With this construction it is not necessary to make the table top strong enough to withstand the pressing forces.

10 The carriage comprises a U-shaped channel 66 having a reinforcing web 67 secured between the flanges of the channel. In order to limit the rearward pivotal movement of the carriage, a toggle comprising links 68 and 69 is provided. The toggle links are pivotally connected together by pin 20 70. Link 69 is pivotally connected to a bracket 71 mounted on the reinforcing web 67 of the carriage. Link 68 is pivotally connected to a bracket 72 secured to the rear side of the cylinder. A coil spring 73, arranged between the end of the carriage and a washer 74 on the pin 70, urges the adjacent ends of the links 68 and 69 toward the lower end of the carriage. When the carriage is in the position shown in full lines in Fig. 1, the force of the spring 73 tends to pivot the carriage rearward and partially overcomes the effect of gravity which holds the carriage in this position. When the carriage is moved to the position shown in dotted lines in Fig. 1, the force of the spring 73 prevents the straightening of the toggle and also cushions the rearward pivotal movement of the carriage.

25 To further cushion the pivotal movement of the carriage, a coil spring 75 is provided around the pin 65. One end of the spring 75 fits within an opening 76 in one of the ears 64, and the other end of the spring is secured to the upper side of reinforcing web 67 by a clamp 77. The spring 75 is arranged so that there is no tension on the spring 40 when the center of gravity of the carriage is vertically above the pin 65. Movement of the carriage on either side of this position causes the spring 75 to be tensioned. The tensioning of the spring 75 still further assists in balancing the 45 force of gravity on the carriage and assists in obtaining easy movement of the carriage.

50 Forward movement of the carriage is limited by an adjustable stop 78 which is secured to the bracket 72 and which is engaged by a projection 79 on the bracket 71. The projection 79 also engages the plunger 80 of a control switch 81 which is also secured to bracket 72.

55 A shoe 82 which is made of aluminum or other suitable metal, is rigidly secured to the upper arm 83 of the carriage. The shoe is placed so that when the carriage is moved to the full line position of Fig. 1, the shoe is in register with the buck and in spaced relation thereto. Since the pivot point of the carriage is below and to the rear of the center line of the buck, that is, a line perpendicular to the top face of the buck passing through the center of the buck, the shoe tends to swing downwardly toward the buck as the carriage is pivoted forward and less clearance is required between the buck and shoe. The location 60 of the pivot point of the carriage provides a more compact construction. The shoe is heated by a heating element 84 which is held in a groove in the upper surface of the shoe by clamps 85 and by a heating element 86 similarly secured in place on

the shoe. The heating element 84 may be controlled by suitable thermostats (not shown) so as to maintain the shoe at proper temperature. The heating element 86, which is preferably chosen to take the same power as the electric motor of the power operated device, is controlled by switch 81. The switch 81 maintains the heating element 86 in an energized condition when the carriage is moved to a position in which the buck and shoe are out of register. When the buck and shoe are moved 10 into register, the switch 81 deenergizes the heating element 86 and closes the circuit to the electric motor. By this arrangement, the electric motor and the heating element 86 are never simultaneously energized and for this reason the 15 power demand of the ironing press is decreased. This provides practically constant power input to the ironing machine and eliminates peak loads while the motor is running. This is important since the power demand of the ironing press 20 should not exceed the capacity of the usual outlet found in homes. A cover 82^a is provided to enclose the upper surface of the shoe. Guards 25 82^b are provided on the front edge of the shoe.

The shoe is moved into and out of register with 25 the buck by a handle connected to the upper surface of the shoe between the shoe and cover 82^a. The handle comprises cross bars 87 and 87^a which are connected between two bars 88 and 89. The bar 89 is pivotally connected to the shoe 30 35 by a stud 90, and a stud 91 extending through an opening 92 in bar 89 allows a limited pivotal movement of the bar 89 around stud 90. Studs 93 extending through enlarged openings 94 in bar 88 hold the bar 88 in place on the upper surface of the shoe and also permit pivotal movement of the handle about the stud 90. This arrangement provides a lost motion connection between the shoe and the handle. The lost motion movement of the handle is used to control the 40 circuit to the motor through a switch 84 having a stationary contact 95 and a movable contact 96. A spring 97 biases the contact 96 toward contact 95. When the handle 87 is pushed in a direction to move the carriage rearward, the handle is 45 pivoted about the stud 90, and a tongue 88 at the end of the bar 88 engages a button 98 of insulating material on the switch and moves the contact 96 out of engagement with contact 95. Since the circuit to the electric motor is closed through 50 these contacts, the opening of the contacts de-energizes the motor and causes the release of pressure between the buck and the shoe. As long as the handle is maintained in this position, the motor cannot be energized. When the handle 55 is released, the spring 97 may be strong enough to close the contacts 95 and 96 and return the handle to the position shown in Fig. 2. This is not necessary since the handle will be returned to the position shown in Fig. 2 by a force on the 60 handle in the direction to move the shoe into register with the buck. This provides a convenient control for the ironing machine since the movement of the handle necessary to control the pressure between the buck and the shoe is the 65 same as that required to move the shoe into and out of register with the buck. If the operator wishes for any reason to release the pressure, it is only necessary to push the handle in the direction to move the shoe out of register with the buck. 70

75 At the right hand end of the shoe is provided a puff iron of the type disclosed and claimed in application Serial No. 741,091, filed August 23, 1934, and assigned to the assignee of this invention. The puff iron is slidably carried in a 75

groove in the upper surface of the shoe below the cover. When not in use, the puff iron is carried within the edges of the shoe in the position shown in Fig. 2. When the puff iron is in use, the working surface 100 of the iron is moved by a handle 101 to a position projecting beyond the edge of the shoe. The portion 102 of the puff iron which is to the rear of the working surface 100 remains within the edges of the shoe and conducts heat from the shoe to the working surface 100 of the puff iron. A spring 103 supported from the shoe by a bracket 104 engages raised portions 105 on the puff iron and holds the puff iron in firm contact with the upper surface of the shoe when the shoe is in the extended and the retracted positions. Between these positions, the spring 103 is out of contact with the upper surface of the puff iron so that the puff iron may be freely moved.

20 In the use of the puff iron, the shoe is moved to the position shown in full lines in Fig. 1, and the puff iron is moved to the extended position by pulling on the handle 101. After the puff iron is moved to the extended position, the handle 25 101 may be swung to one side to uncover the working surface of the puff iron.

As explained above, moving the shoe to the position shown in full lines in Fig. 1 closes the circuit to the electric motor through switches 81 and 94 so that the buck is immediately raised into pressing engagement with the shoe. Since the puff iron may be used for a considerable time, it is undesirable that the buck and shoe be maintained in pressing engagement during this time. 35 An arrangement is, therefore, provided which will open the circuit to the motor and prevent energizing of the motor when the puff iron is moved to the extended position. This arrangement comprises a rod 106, one end of which is pivotally connected to the bar 88 of the handle for moving the carriage. The other end of the rod 106 slidably extends through a hole in a bracket 107 secured to the upper surface of the puff iron. When the puff iron is moved, rod 106 is pivoted 40 about the bar 88. As the puff iron nears the extended position, the rod engages a boss 108 about the bar 88. As the puff iron moves the tongue 98 of the bar 88 against the button 99 and thereby moves contact 96 out of engagement 45 with contact 95. This opens the circuit to the motor and prevents pressing engagement of the buck and the shoe while the puff iron is in the extended position. During the movement of the puff iron, the rod 106 slides through the bracket 107.

55 A diagrammatic view of the control for the ironing press is shown in Fig. 11. In this diagram the current is fed from a suitable source of electricity from conductors 109 and 110 through line 60 switch 111 to contacts 112 and 113. The circuit to heating element 84 on the shoe extends from contact 113 through conductor 114 and conductor 115 to heating element 84 and from heating element 84 through conductor 116 and conductor 117 to contact 112. The circuit to heating element 84 is maintained as long as the line switch 111 is closed.

When the parts are in the position illustrated in Fig. 11, the circuit to the motor is closed and 70 the buck is moved into pressing engagement with the shoe. The circuit to the motor extends from one side of the line through contact 113, conductor 114, conductor 118, contact 95 and contact 96 of switch 94, conductor 119, to one terminal of the motor. From the other terminal

of the motor, the circuit extends through conductor 120, contact 121, switch blade 122 and contact 123 of switch 81, conductor 124, and conductor 117 to the other side of the line. The circuit to the motor is energized when the carriage 5 is moved to the position in which the shoe and buck are in register and when contacts 95 and 96 are in the closed position. When the shoe is in register with the buck, projection 79 on bracket 71 secured to the carriage engages 10 plunger 80 of the switch 81 and moves the switch blade 122 of the switch 80 into engagement with contacts 121 and 123. Contacts 95 and 96 are maintained in the closed position by spring 97 when a force is exerted on the handle 87 in the 15 direction to move the shoe into register with the buck. It is, therefore, apparent that as soon as the shoe is moved into register with the buck, the electric motor is energized and starts to move the buck into pressing engagement with the shoe. 20 To release the pressure between the buck and the shoe, it is necessary to open contacts 95 and 96 by exerting a force on the handle 87 in the direction to move the shoe out of register with the buck. This may be accomplished by pushing on 25 the handle 87 or by moving the puff iron to the extended position.

When the shoe is out of register with the buck, the projection 79 is moved away from the plunger 80 of the switch 81, and spring 125 30 forces the switch blade 122 into engagement with contacts 126 and 127, thus completing a circuit through heating element 86. This circuit may be traced from one side of the line through contact 113, conductor 114, conductor 35 115, heating element 86, conductor 128, contact 126, switch blade 122, contact 127, conductor 124, and conductor 117, to contact 112 and the other side of the line. The circuit to heating element 86 is closed whenever the buck and shoe are out 40 of register.

In the use of the ironing machine, assume that the parts are in the position shown in dotted lines in Fig. 1. In this position, the shoe is out 45 of register with the buck, and the material to be ironed may be arranged over the upper surface thereof. To effect the ironing of the material arranged on the buck, the shoe is moved into register with the buck by pulling on handle 87. The force exerted on the handle causes the handle 50 to pivot about stud 90 thereby moving the tongue 98 of the bar 88 away from the button 99 on switch 94 and permitting contacts 95 and 96 to be moved into engagement by spring 97. Contacts 95 and 96 remain in this position until 55 a rearward force is exerted on the handle. As soon as the shoe reaches a position in register with the buck, projection 79 on bracket 71 attached to the carriage engages plunger 80 of the switch 81 and moves switch blade 122 into engagement with contacts 123 and 121, completing 60 the circuit to the electric motor. Energizing of the electric motor causes rotation of the impeller 22 attached to the lower end of the motor shaft 18. The rotation of the impeller 65 22 draws oil through the inlet opening 27 in the upper side of the piston 11 and forces the oil through openings 28 in the piston head 25 to the lower side of the piston, thereby building up pressure between the piston and the lower end of 70 the cylinder 9 and causing the piston to be moved upward. Due to the time required by accelerating the motor, the building up of pressure between the lower end of the cylinder and the piston is gradual, and the upward movement 75

of the piston is started without shock. The upward movement of the piston continues until the buck is brought into pressing engagement with the shoe, and the resistance offered by the shoe 5 to further movement of the buck balances the pressure created by the impeller. The pressure continues as long as the motor is energized.

Since the shoe is centered above the axis of the cylinder and the carriage is pivoted on the lower 10 end of the cylinder at the axis of the cylinder, the pressing force is not transmitted to the table top and there is no tendency for the cylinder to tilt. The table top is therefore subjected to no additional strain during pressing and need only 15 be strong enough to support the weight of the cylinder and carriage. During pressing, the ribs 38 on the buck rock on shoulders 39 on bearing housing 13 and allow the buck to align its surface with the shoe to maintain an even pressure 20 over the surface of the buck.

Since the center line of the buck passes through a point in front of the pivot point of the carriage, the ironing force is not applied perpendicularly to the surface of the shoe. The 25 ironing force on the shoe comprises a component perpendicular to the surface of the shoe and a component acting along the surface of the shoe in the direction to pivot the carriage forward. The component of force along the surface of the shoe 30 is equal to the product of the perpendicular component of force by the coefficient of friction between the surface of the shoe and the material on the upper surface of the buck. During normal operation of the ironing machine, the torque 35 on the carriage about pin 65 due to the component of the ironing force acting along the surface of the shoe is equal to or greater than the torque on the carriage due to the component of the ironing force perpendicular to the surface 40 of the shoe. The carriage is therefore normally held against stop 18 and there is no slippage between the shoe and the upper surface of the buck. When ironing very dry material at high 45 temperatures of the shoe, the padding on the face of the buck or the material placed on the face of the buck sometimes become sufficiently smooth and slippery so that there is no longer sufficient friction to prevent slippage between the buck and the shoe. Under these circumstances 50 the torque due to the force perpendicular to the surface of the shoe tends to pivot the carriage rearward. This tendency to rearward movement of the carriage is prevented by spacer 43 which restrains rearward tilting of the buck. 55 Unless the buck can tilt rearward, the carriage cannot move rearward during pressing, and slippage between the buck and shoe is accordingly prevented. This arrangement makes it possible 60 to pivot the carriage below and to the rear of the center line of the buck without making any provision for locking the carriage in the position in which the buck and shoe are in register. Forward movement of the carriage during pressing 65 is prevented by stop 78 so that there is no slipping between the buck and shoe during pressing.

To release the pressure between the buck and the shoe, a rearward pressure is exerted on the handle 81 causing the handle to pivot about the 70 stud 90 and thereby causing tongue 98 to press against button 99 and move contact 96 out of engagement with contact 95. Due to the lost motion connection of the handle to the shoe which is provided by the clearance between studs 75 91 and 93 and openings 92 and 94, the pressure

on the handle necessary to open contacts 95 and 96 is slight. When the motor is deenergized, oil flows from the lower side of the piston through openings 28 and 27 to the upper side of the piston. During this movement, the piston 5 operates with the cylinder to cushion the downward movement of the piston. The piston moves downwardly until the buck casting contacts the upper edge of the cylinder 9, as shown in Fig. 6. When the shoe is moved out of register with the 10 buck, the projection 79 on the bracket 71 is moved away from plunger 80 of switch 81, and spring 125 moves switch blade 122 out of engagement with contacts 121 and 123 and into engagement with contacts 126 and 127. Moving the switch 15 blade 122 out of engagement with contacts 121 and 123 opens the circuit to the motor. The movement of switch blade 122 into engagement with contacts 126 and 127 closes the circuit 20 through heating element 86. With this arrangement, the electric motor and heating element 86 can never be simultaneously energized, and the power demand of the press is accordingly decreased. While the buck and shoe are out of register, heating element 86 provides additional 25 power which is available to maintain the shoe at the desired temperature.

No claim is made in this application to the buck construction, this being claimed in my application, Serial No. 744,793, filed Sept. 20, 1934. The combination of an inclined buck with a pivotal carriage for moving the shoe toward and away from the buck is being claimed more broadly in my above application.

The arrangement for receiving the pressing 35 forces independently of the table top by connecting the shoe supporting carriage to the cylinder of the hydraulic operator is being claimed broadly in application, Serial No. 43,937, filed Oct. 7, 1935.

What I claim as new and desire to secure by 40 Letters Patent of the United States, is,—

1. An ironing press comprising a buck, a shoe, an electric heating element for heating the press, electrically operated means for power operation of the press, and means decreasing the power 45 taken by said electric heating element while said electrically operated means is energized for decreasing the power demand of the press.

2. An ironing press comprising a buck, a shoe, an electric heating element for heating the press, 50 electrically operated means adapted when energized to cause pressing engagement of said buck and said shoe and when deenergized to release the pressure between said buck and said shoe, and means decreasing the power taken by said electric 55 heating element while said electrically operated means is energized for decreasing the power demand of the press.

3. An ironing press comprising a buck, a shoe, electrically operated means for power operation 60 of the press, a plurality of electric heating elements for heating the press, and means deenergizing one of said heating elements while said electrically operated means is energized for decreasing the power demand of the press. 65

4. An ironing press comprising a buck, a shoe, a carriage for said shoe, a plurality of electric heating elements for heating the press, electrically operated means for power operation of the press, and a switch operated by said carriage for 70 alternatively energizing said electrically operated means and one of said heating elements.

5. An ironing press comprising a buck, a shoe, means for relatively moving said buck and shoe into and out of register, electrically operated 75

means for relatively moving said buck and shoe into pressing engagement, an electric heating element for heating said press, and means dependent upon said buck and shoe being in register for 5 energizing said electrically operated means and for decreasing the power taken by said heating element.

6. An ironing press comprising a buck, a shoe, means for relatively moving said buck and shoe 10 into and out of register, electrically operated means for relatively moving said buck and shoe into pressing engagement, an electric heating element for heating said press, and means including a switch for energizing said electrically operated 15 means and decreasing the power taken by said heating element when said buck and shoe are in register and for deenergizing said electrically operated means and increasing the power taken by said heating element when said buck and shoe are 20 out of register.

7. An ironing press adapted for use with an electric outlet of limited capacity comprising a buck, a shoe, an electric heating element for heating the press, electrically operated means for 25 power operation of the press, and means decreasing the power taken by said electric heating element while said electrically operated means is energized for increasing the effective heating capacity of the heating element without exceeding 30 the capacity of the outlet.

8. An ironing press comprising a buck, a shoe, power operated means for effecting pressing engagement of the buck and the shoe, a handle for causing relative movement between said buck and 35 said shoe whereby said buck and said shoe are moved into and out of register, means effective upon relative movement of the buck and the shoe by the handle to the in-register position without additional movement of the handle for controlling 40 said power operated means to effect pressing engagement of the buck and the shoe, and means controlled by pressure on said handle in the direction to move said buck and said shoe out of register for controlling said power operated 45 means to release the pressure between said buck and said shoe.

9. An ironing press comprising a buck, a shoe, a handle for moving said shoe into and out of register with said buck, electrically-operated 50 means adapted when energized to cause pressing engagement of said buck and said shoe and when deenergized to release the pressure between said buck and said shoe, a switch controlled by said handle for controlling said electrically-operated 55 means, means for moving said switch to the energized position in response to the force on the handle required to move the shoe into register with the buck, and means for moving said switch to the deenergized position in response to pressure 60 on said handle in the direction to move said shoe out of register.

10. An ironing press comprising a buck, a shoe, a handle for relatively moving said buck and said shoe into and out of register, power-operated 65 means for causing pressing engagement of said buck and said shoe, means actuated by movement of said buck and said shoe into register for controlling said power-operated means to cause pressing engagement of said buck and said shoe, 70 and means controlled by pressure on said handle in the direction to move said shoe and said buck out of register for controlling said power-operated means to release the pressure between said shoe and said buck.

75 11. An ironing press comprising a buck, a shoe,

a handle for relatively moving said buck and said shoe into and out of register, electrically-operated means adapted when energized to cause pressing engagement of said buck and said shoe and when deenergized to release the pressure between said buck and said shoe, means actuated by movement of said buck and said shoe into register for energizing said electrically-operated means, and a switch controlled by pressure on said handle in the direction to move said buck and shoe into and 10 out of register for respectively energizing and deenergizing said electrically-operated means.

12. An ironing press comprising a buck, a shoe, a handle having a lost motion connection with said shoe for relatively moving said shoe into register with and in spaced relation to said buck and for moving said shoe out of register with said buck, electrically-operated means adapted when energized to cause said buck to be raised into pressing engagement with said shoe and when deenergized to cause the buck to be lowered, means actuated by movement of said shoe into register with said buck for energizing said electrically-operated means, and a switch controlled by the lost motion movement of said handle for controlling the energizing of said electrically-operated means.

13. An ironing press comprising a support, a tiltably mounted buck carried by the support, a carriage pivoted on the support below said buck 30 and pivotally movable forward and rearward with respect to said buck, a shoe carried by said carriage and movable to a position above and in register with said buck, means for relatively moving said buck and shoe into pressing engagement, and 35 means restraining rearward tilting of said buck for preventing rearward movement of said carriage during pressing.

14. An ironing press comprising a buck, a shoe, means for moving said buck and said shoe into 40 pressing engagement, a puff iron carried by said press movable to an operative and an inoperative position, means dependent upon said puff iron being moved from the inoperative position for preventing pressing engagement of said buck and said shoe.

15. An ironing press comprising a buck, a shoe, power-operated means for moving said buck and said shoe into pressing engagement, a puff iron carried by said shoe having a working surface movable to a position projecting beyond said shoe, and means dependent upon the working surface of said puff iron being moved beyond said shoe for controlling said power-operated means to prevent pressing engagement of said buck and said shoe.

16. An ironing press comprising a buck, a shoe, means for relatively moving said buck and shoe into and out of register, power-operated means for causing pressing engagement of said buck and said shoe, means dependent upon said buck and shoe being in register for controlling said power-operated means to cause pressing engagement of said buck and said shoe, a puff iron carried by said press movable to an operative and an inoperative position, and means dependent upon said puff iron being moved from the inoperative position for controlling said power-operated means to prevent pressing engagement of said buck and said shoe.

17. An ironing press comprising a buck, a shoe, 70 a handle for moving said buck and said shoe into and out of register, electrically-operated means for controlling the pressing engagement of said buck and said shoe, a switch controlled by pressure of said handle in the direction to move said

- buck and shoe into and out of register for controlling said electrically-operated means to respectively cause pressing engagement and release of pressure between said buck and said shoe.
- 5 5 a puff iron carried by said shoe movable to an operative and an inoperative position, and means dependent upon said puff iron being moved from the inoperative position for controlling said switch to prevent pressing engagement of said 10 buck and said shoe.
- 10 18. An ironing press comprising a support, a buck having its surface inclined upwardly from the front, a shoe, means for moving said shoe to a position in register with said buck, and means 15 for moving said buck into pressing engagement with said shoe.
- 15 19. An ironing press comprising a table having an opening therein, a cylinder carried by the table in said opening, a piston in said cylinder, 20 a buck on said piston, a carriage pivoted on said cylinder below said buck, a shoe carried by said carriage and movable to a position in register with said buck, and means including said piston for moving said buck into pressing engagement 25 with said shoe.
- 20 20. An ironing press comprising a buck having its surface inclined upwardly from the front, a cylinder having its axis inclined downward and rearward of the center line of the buck, a piston 30 in said cylinder, a carriage pivoted on said cylinder below and to the rear of the center line of the buck, a shoe carried by the carriage and movable to a position in register with said buck, and means including said piston for moving said buck 35 into pressing engagement with said shoe.
- 25 21. An ironing press comprising a buck having its surface inclined upwardly from the front, a cylinder having its axis inclined downward and rearward of the center line of the buck, a piston 40 in said cylinder, said buck being tiltably mounted on said piston, a carriage pivoted on said cylinder below and to the rear of the center line of the buck, a shoe carried by said carriage movable to a position in register with said buck, means including said piston for moving said buck into 45 pressing engagement with said shoe, and means restraining rearward tilting of said buck for preventing rearward movement of said carriage during pressing.
- 45 50 22. In an ironing press, a support, a buck carried by said support, a carriage pivoted on said support below said buck, said carriage having an arm extending above said buck, a shoe carried by said arm, a toggle including a pair of links 55 connected to each other and respectively connected to said support and said carriage for limiting the pivotal movement of said carriage, and a spring connected to said support for preventing straightening of said toggle and for cushioning the pivotal movement of said carriage.
- 55 60 23. An ironing press comprising a buck, a carriage pivoted below and to the rear of the center line of the buck, a shoe carried by said carriage movable to a position in register with said buck, 65 and means moving said buck into pressing engagement with said shoe along an axis passing through the pivot point of the carriage.
- 65 70 24. An ironing press comprising a tiltably mounted buck, a carriage pivoted below and to the rear of the center line of the buck, a shoe carried by said carriage movable to a position in register with said buck, means moving said buck into pressing engagement with said shoe along an axis passing through the pivot point of 75 the carriage, and means restraining rearward
- tilting of the buck for preventing rearward movement of the carriage during pressing.
- 75 80 25. An ironing press comprising a table having an opening therein, a cylinder carried by the table in said opening, a piston in said cylinder, a buck on said piston, a carriage, a shoe carried by said carriage and movable to a position in register with said buck, means including said piston for moving said buck into pressing engagement with said shoe, and means on said cylinder 10 engaging said carriage for transmitting the pressing forces from said cylinder to said carriage.
- 10 15 26. An ironing press comprising a pair of cooperating pressing members, means for mounting one of said members for movement transversely to the other pressing member into and out of register therewith, a handle connected to said movable pressing member so as to have lost motion in the direction of movement of the pressing member, power operated means for effecting 20 pressing engagement of said pressing members, and means controlled by the lost motion movement of said handle for controlling said power operated means, said means being actuated to control the power operated means to cause pressing engagement of said pressing members by the pressure on the handle required to move the pressing members into register and being actuated to control the power operated means to release the pressure between the pressing members 25 by pressure in the direction to move said pressing members out of register.
- 25 30 27. In an ironing press, a hollow buck having an upper wall provided with openings for the passage of steam, a pad on said upper wall, a 35 conduit leading from said buck to drain the condensate from the interior of the buck, and a receptacle for receiving the condensate from said conduit, said receptacle being provided with a wall closely adjacent the end of said conduit 40 whereby the liquid in the receptacle will serve as a seal and prevent the discharge of steam from the conduit.
- 35 40 28. In an ironing press, a hollow buck having an upper wall provided with openings for the passage of steam, a pad on said upper wall, a conduit leading from said buck to drain the condensate from the interior of the buck, and a trap 45 arranged to be filled with the condensate for preventing escape of steam from said conduit.
- 45 50 29. An ironing press comprising a buck having its surface inclined upwardly from the front, supporting means for said buck, a carriage supported by said supporting means below and to the rear of the center line of the buck so as to have pivotal movement with respect to said buck, a shoe carried by said carriage and movable thereby to a position above and in register with said buck, and means for moving said buck into pressing engagement with said shoe.
- 50 55 30. An ironing press comprising a table having a top provided with an opening, a structure supported from the table top and extending through said opening, a carriage pivoted on said structure below said table top, said carriage having an arm movable to a position above said table top, a buck above said table top, a shoe carried by said arm and movable to a position above said buck, and a pressure developing mechanism carried by said structure and arranged to develop pressure between said carriage and said buck whereby pressing engagement between said buck and said shoe is effected.
- 55 60 31. An ironing press comprising a buck, a carriage pivoted below and to the rear of the center

- line of the buck, a shoe carried by said carriage and movable to a position above and in register with said buck, and means for effecting pressing engagement between said buck and said shoe by 5 relative movement of said buck and said shoe along an axis inclined downward and rearward of the center line of the buck.
32. An ironing press comprising a buck, means for tiltably supporting said buck, a carriage pivoted below and to the rear of the center line of the buck, a shoe carried by said carriage and movable to a position above and in register with said buck, means for effecting pressing engagement of said buck and said shoe by relative 10 movement of said buck and said shoe along an axis inclined downward and rearward of the center line of the buck, and means restraining rearward tilting of said buck for preventing rearward movement of said carriage during pressing.
33. In an ironing press comprising a pair of co-operating pressing members, means for mounting one of said members for movement transversely to the other pressing members into and out of register therewith, a handle connect- 15 ed to said movable pressing member, power operated means for the press, means actuated by movement of said movable pressing member into register with the other pressing member for controlling said power means to effect pressing engagement of the pressing members, and means responsive to pressure on said handle in the direction to move the movable pressing member to the out-of-register position for controlling said power 20 means to release the pressure between the pressing members.
34. In an ironing press comprising a pair of co-operating pressing members, a handle for effecting relative movement of the pressing members into and out of register with each other, elec- 25 trically operated means adapted when energized to effect pressing engagement of said members and when deenergized to release the pressure between said members, a switch controlled by said handle for controlling said electrically operated means, means for moving said switch to the energized position in response to the force on the handle required to effect the movement of the pressing members to the in-register position, and means for moving said switch to the deenergized position in response to pressure on the handle in the direction to effect movement of said members out of register.
35. In an ironing press comprising a pair of co-operating pressing members, a handle for effecting relative movement of said members into and out of register, power operated means for effecting pressing engagement of said members, means actuated by movement of said members into register for controlling said power operated means to effect pressing engagement of said members, and means controlled by pressure on said handle in the direction to move said members out of register for controlling said power operated means to release the pressure between said members.
36. An ironing press comprising a pair of co-operating members, means for moving said pressing members into pressing engagement, a puff iron carried by said press movable to an operative and an inoperative position, means dependent upon said puff iron being moved from the inoperative position for preventing pressing engagement of said pressing members.
37. An ironing press comprising a pressing member, a shoe, power-operated means for moving said pressing member and said shoe into pressing engagement, a puff iron carried by said shoe having a working surface movable to a position projecting beyond said shoe, and means dependent upon the working surface of said puff iron being moved beyond said shoe for controlling said power-operated means to prevent pressing engagement of said pressing member and said shoe.

GEORGE W. WARDWELL, JR.
